UNITED STATES PATENT OFFICE.

FRANK RUDOLPH, OF BEASON, ILLINOIS.

TWO-WHEELED VEHICLE.

SPECIFICATION forming part of Letters Patent No. 398,801, dated February 26, 1889.

Application filed August 16, 1888. Serial No. 282,858. (No model.)

To all whom it may concern:

Be it known that I, FRANK RUDOLPH, a citizen of the United States of America, residing at Beason, in the county of Logan and State of Illinois, have invented certain new and useful Improvements in Vehicles; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

My invention relates to certain new and useful improvements in vehicles, the object thereof being to provide a single or double sulky, by the construction of which the seat will be located rear of the axle, so as to counterbalance the weight of the pole or thills, thereby placing but little weight upon the horse and overcoming the up-and-down movement of the horse.

My invention also consists in providing a spring-support for the seat located to the rear of the axle; also in the construction and combination of the parts, as will be hereinafter fully set forth, and specifically pointed out in the claim.

In the accompanying drawings, Figure 1 is a perspective view of the leading features of my improvement, the seat being shown in dotted lines. Fig. 2 is a plan view. Fig. 3 is a sectional view. Fig. 4 is a plan view showing the application of thills or shafts to the vehicle.

A refers to the axle, which is upwardly curved centrally, and provided on its upper edge with a strip of bent wood, a, clipped thereto by clips, located as shown.

The spring B is semi-elliptical, the ends being also bent upwardly and formed into eyes. To the center portion of the spring is clipped, by a suitable shackle, b, a seat-supporting bar, C, the ends of which diverge outwardly and then bend horizontally, at which point they are perforated and bolted to the under side of the seat at a suitable distance rear of the axle.

The ends of the semi-elliptical spring B are connected to the axle by rods D and E, the rods D extending horizontally rearwardly from the axle, their front ends being secured

by clips d to the under side of the axle. The outer ends of the bars D in front of the spring are provided with collars e, beyond which the rods D are rounded to pass through the eyes formed in the ends of the springs, and from these rounded portions the lower ends of the rods E pass, and are secured either by upsetting the ends of the rods D or by the employment of nuts.

The rods E incline inwardly and upwardly toward the axle, and are secured thereto by suitable bolts. By thus arranging the rods E and D the spring is supported rear of the axle, and the ends are thoroughly braced against downward movement, the lateral movement of the vehicle being taken up by the upwardly-curved ends of the spring B, said ends being the most elastic portion thereof.

The pole F is attached centrally at its rear end to a circular bar, G, the ends of which are secured to the axle by means of the rods H, which are attached to the rear ends of said circle-bar G and clipped to the axle by clips h, the front ends of these bars H extending forwardly and upwardly to the pole beneath the singletree, where they are rigidly attached to the pole by suitable bolts.

The circle-bar G and the brace-rods H are connected to the axle by brace-rods E', which are secured to the axle by the same bolt which secures the rear brace-rods, E, thereto.

Connected to the pole at a point rear of the singletree is a cross-bar, I, which is also connected to the rods by suitable bolts. The ends of this cross-bar I are provided with staples, to which are hinged short rods or spring i, which are curved downwardly. The rear ends of these bars or springs are attached to a curved bar, K, which extends upwardly and rearwardly, and is secured to the under side of the seat at a point slightly rear of the axle.

When a pole is used, the cross-bar I will serve as a foot-rest; or suitable cross-pieces may be provided, so as to form a floor.

When thills are employed, as shown in Fig. 4 of the accompanying drawings, the cross-bar I may be dispensed with, and the curved seat-supporting bar K can be attached directly to the thills, as shown, and to the under side of the seat can be attached outwardly-diverging bars or supports which will extend forwardly under the axle, and from

thence curved upwardly to the thills near the whiffle-tree, said bars being designed to support slats upon which the feet of the driver may rest; or, if desirable, suitable foot-rests 5 can be attached to these bars, as shown.

The vehicle hereinbefore described will be extremely light, and the seat is so located that neither the horse-movement nor the movement caused by the roughness of the road 10 will be felt by the occupant of the seat.

Having thus described my invention, what I claim as new, and desire to secure by Letters Patent, is—

In a vehicle, the combination of an upwardly-bowed axle, a semi-elliptical spring, B, connected to the axle by rearwardly-extending horizontal bars D, connected to clips on

the axle, and brace-rods E, which extend from the outer ends of the rods D upwardly and inwardly and bolted to said axle, a bar, C, secured to the said spring B, and having outwardly-spreading bent ends adapted to be secured to and support the seat, the pole or thills having a cross-bar, I, secured thereto, the circle-bar K, secured to the seat, having 20 spring-extensions i, attached to the cross-bar I, the curved bar G, and the brace-rods H and E', substantially as described.

In testimony whereof I affix my signature in presence of two witnesses.

FRANK RUDOLPH.

Witnesses:

F. C. Houser,
DAVID A. GORMAN.
